Fig. 4

FIG. 1 is a top plan view of an alarm container showing our new design;

FIG. 2 is a front elevational view thereof;

FIG. 3 is a right end elevational view thereof; and

FIG. 4 is a bottom view thereof.

The perforations are partially shown in the center section of the housing for convenience of illustration, it being understood that the perforations are uniformly continuous over the area in which they appear.

We claim:

The ornamental design for an alarm container, as shown and described.
